(57) **CLAIM**

The ornamental design for an oven rack cleaning device, as shown and described.

DESCRIPTION

FIG. 1 is a top, front, left side perspective view of an oven rack cleaning device embodying my design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof, the right side being a mirror image thereof;

FIG. 7 is a cross-sectional view thereof along lines 7—7 shown in FIG. 2; and,

FIG. 8 is a cross-sectional view thereof along lines 8—8 shown in FIG. 2.
